DESIGN FOR A SHRINE OR SIMILAR ARTICLE

Walter Barbanell, New York, N. Y.

Application November 26, 1946, Serial No. 135,079

Term of patent 14 years

(Cl. D29—23)

To all whom it may concern:

Be it known that I, Walter Barbanell, a citizen of the United States, residing in New York city, in the county of New York and State of New York, have invented a new, original, and ornamental Design for a Shrine or Similar Article, of which the following is a specification, reference being had to the accompanying drawing, forming part thereof.

Fig. 1 is a front perspective view of a shrine or similar article showing my design.

Fig. 2 is a rear perspective view of the shrine or similar article.

The design is characterized by the portions shown on the drawing in full lines.

I claim:

The ornamental design for a shrine or similar article, substantially as shown and described.

WALTER BARBANELL.
